HIS ATTORNEY'S

UNITED STATES PATENT OFFICE.

WILLIAM W. DEAN, OF LOWELL, MASSACHUSETTS, ASSIGNOR TO THE EFFICIENCY ELECTRIC CORPORATION, OF NEW YORK, N. Y., A CORPORATION OF NEW YORK.

PHONOGRAPH STOP MECHANISM.

Application filed April 15, 1922. Serial No. 552,986.

To all whom it may concern:

Be it known that I, WILLIAM W. DEAN, a citizen of the United States, residing at Lowell, in the county of Middlesex and State 5 of Massachusetts, have invented certain new and useful Improvements in Phonograph Stop Mechanisms, of which the following is a full, clear, concise, and exact description, such as will enable others skilled in the art 10 to which my invention appertains to make and use the same.

My invention relates to phonograph stop mechanisms, and particularly to such stop mechanisms as are known in this art as present 15 phonograph stop mechanisms.

It is an object of the present invention to provide a mechanism having an element adapted to be adjusted prior to the playing of a phonograph record to a particular position in the path of the advancing tone arm, and which element comprises an electrical switch controlling member, such element having a handle portion projecting above the horizontal plane of the tone arm, and which handle portion may be grasped by the operator of the phonograph as for the purpose of adjustment.

Another object of my invention is to provide such an element as above referred to 30 which is entirely self-contained, and which comprises an electrical switch and a switch operating lever, same being enclosed in the body of the stop element, and which switch is protected from dust and moisture which 35 otherwise might interfere with the proper working of the switch contacts.

Another object of my invention is to provide such a stop element containing an electrical stopping switch, and in which the 40 switch contacts are capable of ready access as for repair or adjustment, and which may be inexpensively manufactured and easily assembled, and which may be so made as to be presentable in appearance as well as efficient in operation when used.

Another object of my invention is to provide such a stop element as may be mounted 50 on the upper face of the phonograph driving mechanism enclosing casing of the well known makes of phonographs employing disc records.

Another object of my invention is to provide an electrically controlled automatically 55 operated phonograph stopping mechanism comprising an actuating electromagnet

adapted to operate under the control of the said switch, when the said switch is operated at the termination of a record which has been played.

Another object of my invention is to provide such an electrically operated stop mechanism which, with its enclosing casting, is so thin that it may be placed under the phonograph turn table on the board comprising a wall of the motor enclosing cabinet.

Another object of my invention is to provide such an electrically operated stop mechanism operable under the control of the said switch, and which comprises a second switch, 60 said second switch being operable to close its contacts when the operator moves the phonograph motor starting lever, and which starting lever is automatically restored to normal stopping position under the control of 65 the said first switch, and the said electromagnet.

Other objects of my invention and the invention itself will be more apparent as the description of the embodiment thereof, 70 herein illustrated and described, progresses, and which embodiment is shown in the accompanying drawings forming a part of this specification, and in which drawings—

Fig. 1 shows a top plan view of a phonograph mechanism embodying my invention.

Fig. 2 shows a side elevational view of the supporting board, and phonograph elements together with the motor secured to the under side of the supporting board of such a phonograph mechanism as illustrated in 90 Fig. 1.

Fig. 3 shows a side elevational view of the electrical switch enclosing phonograph tone arm engaging stop element of my invention.

Fig. 4 shows a top plan view of the said stop element shown in Fig. 3.

Fig. 5 shows the stop element of Fig. 3 in side elevation, but with the outside cover plate removed so as to expose the inner operative switch parts.

Fig. 6 shows a top plan view of the electrically controlled electromagnetically operated stop mechanism comprised in my invention, but with the top cover plate therefor removed so as to expose the inner electrically controlled and controlling mechanism.

Fig. 7 is a sectional view taken on the line A—A of Fig. 6 looking in the direction of the arrows shown for the said line.

Fig. 8 shows a sectional view taken on the line B—B of Fig. 6 looking in the direction of the arrows indicated for the said line.

Fig. 9 shows an elevational view of the terminal block comprised in the apparatus of Fig. 6.

Fig. 10 is a diagram of the electrical circuits involved in the illustrated embodiment of my invention.

10 Fig. 11 is a side elevational view of the apparatus of Fig. 6, but with the cover plate therefor in place.

15 Fig. 12 shows an elevational view of the stop element of Fig. 3 viewed from the direction of the approaching tone arm.

20 Referring now to all of the figures in which like parts are indicated by like reference characters, at 1 is shown the top wall of a phonograph motor enclosing casing, 20 and which wall is commonly made of wood and forms a supporting board for the phonograph motor 2 which is attached to its underside, and which motor, in the present embodiment of my invention, is an electrical 25 motor.

25 The electrical motor 2 is adapted to rotate the phonograph turn-table 3 by means of a turn-table shaft 4 supporting the said turn-table and rotated by the motor 2 through suitable gearing, not herein shown, but well known in the art.

30 The electrical circuits for the electric motor 2 are illustrated diagrammatically in Fig. 10 wherein at 5 are shown a pair of circuit conductors leading from a source of electrical current, not herein shown, to the phonograph motor mechanism, the said electrical conductors 5 connecting in serial circuit, the field windings 6 and the armature 7 of the motor 2, and an electrical switch contact set 8, said contact set when its contacts are closed being adapted to cause the energization of the said motor windings from the said source of current to operate the motor.

40 45 The electrical circuits shown in Fig. 10 comprise also a branch circuit comprising an electro-magnet 9 adapted, when energized, to interrupt the circuit closed by the contacts 8, and an electrical switch comprising normally open contacts 10, which contacts 10 when closed after the phonograph has been started, are adapted to energize the electro-magnet 9 to trip to open circuit position the contacts 8.

50 55 Referring now particularly to Figs. 3 to 5 inclusive, it will be seen that the switch contacts 10 are carried on a pair of resilient switch springs 11 and 12, and with an actuating switch controlling spring 13, are enclosed in an elongated compartment 14 in the phonograph stop pre-set member 15; the said member comprising an outer casting of electrical insulating material such as bakelite or other equivalent material for the purpose.

The stop element shown in Figs. 3 to 5 inclusive, comprises a base member 16, and an adjustable stop element member 15, the said base member comprising a bottom base portion 17 and upwardly extending flanges 18 and 19, the element 15 being disposed between the flanges 18 and 19 and secured thereto by a bolt 20 passing through an opening 21 of the element 15, and an aligned opening in the flange 18 being screw threaded into the other flange member 19; in this way the element 15 is frictionally, but rotatably held between the two flanges of the base member 16. The springs 11 and 12 carrying the switch contacts 10 are secured by machine screws 22 and 23 to a wall 24 of the enclosing element 15, each of said springs being electrically insulated from the other.

55 The switch actuating spring 13 is snapped into place within a slot 25 disposed within the chamber 14 of the element 15 and near the bottom of the said chamber, the slot being so shaped and the spring 13 being so formed that the spring 13 will be given a bias toward the wall 26 of the chamber 14 within the element 15.

60 The spring 13 carries near its free end, a contact element 27 of insulating material adapted to contact when the spring 13 is deflected inwardly with the end of the spring 11 so as to cause the electrical contact 10 carried by the spring 11 to engage the electrical contact 10 carried by the spring 12 so as to close the said contacts and establish an electrical circuit between the circuit conductors 28 and 29 leading to the springs 11 and 12 respectively.

65 The spring 13 carries near its free end an outwardly extending flange 30 which projects through a slot 31 in the wall 26 of the element 15.

70 The element 15 has a nob handle end portion 32 adapted to be manually grasped to rotate the element 15 about its supporting shaft, the bolt 20 disposed through the opening 21 of the said element.

75 The element 15 is relatively long and need only be rotated through a small arc in order to accommodate itself to any desired set position, or inoperative position. I am thus enabled to pivot the element 15 that it will rotate in a vertical plane and be mounted on the supporting board 1 of phonographs varying widely in design, and the element 15, moreover, so constructed, may be manually operated by the operator taking hold of the nob 32, or when pre-setting before starting a record will be thrown toward the tone arm manually, and then the tone arm will be operative to pre-set the element 15 by the operator swinging the tone arm to the end-of-record position. When so pre-set upon playing the record, and the tone arm again reaching the end-of-record position will press the flange 30 of the spring 80

13 inwardly to flex the said spring to cause its insulating contact 27 to force the contacts 10 of springs 11 and 12 together, thus closing a circuit through the contacts 10 for the phonograph stop, or tripping magnet 9.

The tripping mechanism comprising the magnet 9 is illustrated in Figs. 6 to 9 inclusive, in considerable detail. Referring to the said figures, the magnet 9 is shown as 10 being supported on the frame 33 by machine screws 34 passing through a turned-over flange 35 of the base 33, and which screws 34 are screw threaded in the core 36 of the magnet 9, said core projecting from the end 15 of the magnet 9 sufficiently for the purpose. The other end of the core comprising the pull piece 37 projects but slightly through the end of the magnet winding 9, and in front of the said pull piece an electro magnet armature 38 is placed, the said armature being pivoted at 39 on a rod 40 secured to the base 33 at 41, and to a turned-over flange portion 42 thereof.

A rearwardly extending arm 43 of the 25 armature 38 is adapted to be moved to engage a notched portion 44 of a starting and stop lever 45 which is pivoted at 46 on the said casting 33 in order to stop the phonograph motor whenever the electro-magnet 9, being energized, attracts the armature 38.

An electric switch comprising a pair of normally opened contacts 8, is carried on the base 33, resilient springs 48 and 49 carrying the contacts 8 being mounted on a flange 50 of the base 33, the said flange being disposed at right angles to the said base, and the springs being secured between insulating washers 15 by machine screws 52 passing through openings in the said washers, and somewhat larger openings in the said springs, and through a clamping plate 53, the ends of the said screws being screw threaded into the said flange 50, the end 54 of the spring 49 which I term the actuating spring is disposed at an angle to the body of the spring and is adapted to engage the outer peripheral surface 55 of a roller 56 loosely and rotatably carried on the end 57 of the lever 45 distant from the handle 58 of the lever handle.

The handle 58 supported on the outer end of the lever 45 and projecting upwardly therefrom carries on its inner upper end 60 a friction contact element such as the felt pad 59, such pad being fitted tightly within a cylindrical recess 61 in the said handle 58.

The lever 45 has its handle portion extending through an opening 63 in the casting 33, said opening being provided by the omission of a portion of the flanged side members 62 of the base 33, the said side members projecting upwardly from the said base.

The opening 63 is made sufficiently wide 65 as to permit the lever 45 to be rotated

through a considerable angle about its pivot 46. The pivot 46 consists of a rivet having an enlarged head 47, the end of the rivet 48 being tightly secured as by riveting or peening in an opening through the base member 33. 70

The contact pad 59 and the handle 58 are sufficiently elevated above the level of the body of the lever member 45 that the contact pad 59, may, in the position assumed by the lever 45, as shown in Fig. 6, engage with the flanged rim 64 of the turn-table 3, a section of the said flanged rim being shown in Fig. 6 with the friction pad 59 shown in frictional engagement therewith whereby 75 the said pad prevents the rotation of the turn-table. 80

It will be noted that in such a position, the lever 45 is disposed at an angle to a diameter of the turn-table, and in such a 85 direction that the turn-table direction of rotation, when the turn-table rim 64 engages the pad 59, tends to increase this angle so that a binding frictional contact is had between the said pad and the said rim. 90

The operation of the mechanism of my invention is briefly as follows—

The operator places a phonograph record on the turn-table, and after deflecting the element 15 toward the tone arm, moves the tone arm inwardly toward the center of the record until the reproducer 66 has taken that position which it will later assume when it reaches the end of the record, and the tone arm 67 will have made contact with the contact piece 30 of the element 15 and caused the said element to rotate rearwardly about its center of rotation 21, and then the operator, having completed what is termed the "pre-setting" operation, manually rotates 100 the lever 58 counterclockwise. 105

This causes the disengagement of the friction contact pad 59 with the turn-table 64, thus permitting the turn-table to rotate when the electric motor 2 is started. The 110 motor 2 is started by the movement of the lever 58, since such movement causes a camming of the actuating contact spring 49 by the rotatable roller 56 whose face 55 engages normally the turned end 54 of the said spring, so that the actuating spring is moved to contact closing position wherein the contacts 8 are closed. The contacts 8 being in the energizing circuit of the motor 2, when closed, therefore, connect the incoming circuit conductors 5 from the source of energizing current to the said windings of the said motor, and the motor is thereby started. 115

The motor will operate at substantially a 120 constant speed under the control of the governing apparatus indicated generally by the numeral 69, Fig. 10, and the turntable 3 being freed from the restraint of the friction pad 59, will be rotated by the power of the 125 said motor transmitted to the turn-table by 130

suitable reducing gear mechanism, not shown. The turn-table will continue to rotate and the spirally grooved record will direct the tone arm 67 toward the center of the record; the tone arm rotating clock-wise until it engages with the contact piece 30 carried on the spring 13 of the element 15, and such engagement will flex the spring 13 until the spring carried contacts 10 are closed by the engagement of the insulating contact 27 with the actuating contact spring 11, moving the spring 11 toward the spring 12 to close the contacts 10.

The contacts 10 being closed, the energizing circuit for the magnet 9 will be completed from the source of current, and the magnet will attract its armature 38 and the rearwardly extending arm 42 of the said armature will be rotated counter-clockwise about a center 39, and will engage the notched portion 44 of the lever 45 and exert a pressure against the said lever to force the same in a clock-wise direction about its center 46, and after a certain amount of lever movement under the power of the armature 38, the power of the spring 49 will reinforce that applied by the armature arm 43 to accelerate the rate of movement of the said lever 58 to cause it to be snapped into turn-table rim engaging position as shown in Fig. 6, wherein the contact pad 59 frictionally engages the rim 64.

Also, as has been explained, the clockwise rotation of the turn-table 64 before coming to rest, will, by frictional engagement with the pad 59, tend to so move the lever 45 that the pad 59 will make even closer engagement and a tighter contact with the rim of the turn-table, so that the turn-table will quickly be brought to rest and held against movement, the motor circuit, having been interrupted by the breaking of the contacts 8 upon the clockwise rotation of the said lever 45.

Having thus described my invention in a specific embodiment, I am aware that numerous and extensive departures may be made from the embodiment herein illustrated and described, but without departing from the spirit of my invention, I claim:

1. In a pre-set phonograph stop mechanism, the combination with a phonograph starting lever, said lever adapted to have normal and advanced operative positions, a phonograph turn-table, motor means to rotate the said turn-table, said motor means being responsive to the movement of the said lever from its normal to its advanced position to rotate the said turn-table, electro-magnetic means adapted when energized to restore the said lever from its advanced to its normal position, an electric switch controlling the energization of the said electro-magnetic means, and means responsive to the movement of the tone arm to substantially

its end-of-record playing position to operate the said switch.

2. In a pre-set phonograph stop mechanism, the combination with a phonograph starting lever, said lever adapted to have normal and advanced operative positions, a phonograph turn-table, motor means to rotate the said turn-table, said motor means being responsive to the movement of the said lever from its normal to its advanced position to rotate the said turn-table, electro-magnetic means adapted when energized to restore the said lever from its advanced to its normal position, an electric switch controlling the energization of the said electro-magnetic means, and means responsive to the movement of the tone arm to substantially its end-of-record playing position to operate the said switch, said switch comprising a pair of normally open contacts, and an actuating lever for the said contacts adapted to be disposed in the path of the advancing tone arm, and adjusting means for the said actuating lever adapted to adjust the said lever to different contact closing positions in the path of the said tone arm.

3. In a pre-set phonograph stop mechanism, the combination with a phonograph starting lever, said lever adapted to have normal and advanced operative positions, a phonograph turn-table, motor means to rotate the said turn-table, said motor means being responsive to the movement of the said lever from its normal to its advanced position to rotate the said turn-table, electro-magnetic means adapted when energized to restore the said lever from its advanced to its normal position, an electric switch controlling the energization of the said electro-magnetic means, said means responsive to the movement of the tone arm to substantially its end-of-record playing position to operate the said switch, a casing for the said switch enclosing the same, said casing comprising walls of insulating material, a base for supporting the said casing, said casing being rotatably secured to the said base, means for frictionally holding the said casting in any pre-set rotative position, an actuating element adapted to project through a wall of said casting, and adapted to be disposed in the path of the advancing phonograph tone arm, said actuating element when engaged by the said tone arm adapted to close the contacts of the said switch.

4. In a pre-set phonograph stop mechanism, the combination with a phonograph starting lever, said lever adapted to have normal and advanced operative positions, a phonograph turn-table, motor means to rotate the said turn-table, said motor means being responsive to the movement of the said lever from its normal to its advanced position to rotate the said turn-table, electro-magnetic means adapted when energized to restore the

5 said lever from its advanced to its normal position, an electric switch controlling the energization of the said electro-magnetic means, and means responsive to the movement of the tone arm to substantially its end-of-record playing position to operate the said switch, said lever in its normal position making frictional engagement with the said turn-table to frictionally hold it 10 against rotation.

6. In a pre-set phonograph stop mechanism, the combination with a phonograph starting lever, said lever adapted to have normal and advanced operative positions, a 15 phonograph turn-table, motor means to rotate the said turn-table, said motor means being responsive to the movement of the said lever from its normal to its advanced position to rotate the said turn-table, electro-magnetic 20 means adapted when energized to restore the said lever from its advanced to its normal position, an electric switch controlling the energization of the said electro-magnetic means, and means responsive to the movement of 25 the tone arm to substantially its end-of-record playing position to operate the said switch, a pair of normally open switch contacts adapted to be closed responsive to the movement of the said lever to motor starting 30 position.

7. In a pre-set phonograph stop mechanism, the combination with a phonograph starting lever, said lever adapted to have normal and advanced operative positions, a 35 phonograph turn-table, motor means to rotate the said turn-table, said motor means being responsive to the movement of the said lever from its normal to its advanced position to rotate the said turn-table, electro-magnetic 40 means adapted when energized to restore the said lever from its advanced to its normal position, an electric switch controlling the energization of the said electro-magnetic means, and means responsive to the movement of 45 the tone arm to substantially its end-of-record playing position to operate the said switch, said lever in its normal position making frictional engagement with the said turn-table to frictionally hold it against rotation, a pair of normally open switch contacts adapted to be closed responsive to the movement of the said lever to motor starting 50 position.

8. In a pre-set phonograph stop mechanism, the combination with a phonograph starting lever, said lever adapted to have normal and advanced operative positions, a 55 phonograph turn-table, motor means to rotate the said turn-table, said motor means being responsive to the movement of the said lever from its normal to its advanced position to rotate the said turn-table, electro-magnetic 60 means adapted when energized to restore the said lever from its advanced to its normal position, an electric switch controlling the

energization of the said electro-magnetic means, and means responsive to the movement of the tone arm to substantially its end-of-record playing position to operate the said switch, a casting for the said switch enclosing the same, said casting comprising walls of insulating material, a base for supporting the same casting, said casting being rotatably secured to the said base, means for frictionally holding the said casting in any 70 pre-set rotative position, an actuating element adapted to project through a wall of the said casting, and adapted to be disposed in the path of the advancing phonograph tone arm, said actuating element when engaged by the said tone arm adapted to close the contacts of the said switch, said lever in its normal position making frictional engagement with the said turn-table to frictionally hold it against rotation, a pair of 80 normally open switch contacts adapted to be closed responsive to the movement of the said lever to motor starting position.

9. In a pre-set phonograph stop mechanism, the combination with a phonograph starting lever, said lever adapted to have normal and advanced operative positions, a phonograph turn-table, motor means to rotate the said turn-table, said motor means being responsive to the movement of the tone arm to substantially its end-of-record playing position to 90 operate the said switch, a pair of normally open switch contacts adapted to be closed responsive to the movement of the said lever from its advanced to its normal position, an electric switch controlling the energization of the said electro-magnetic means, and means responsive to the movement of the tone arm to substantially its end-of-record playing position to 95 operate the said switch, a spring associated with the said starting lever and adapted to accelerate its movement toward normal position, said spring being so disposed relative to the said lever that it will be ineffective to tend to move said lever from its fully advanced record playing position.

10. In a pre-set phonograph stop mechanism, the combination with a phonograph starting lever, said lever adapted to have normal and advanced operative positions, a phonograph turn-table, motor means to rotate the said turn-table, said motor means being responsive to the movement of the tone arm to substantially its end-of-record playing position to 110 operate the said switch, a spring associated with the said starting lever and adapted to accelerate its movement toward normal position, said spring being so disposed relative to the said lever that it will be ineffective to tend to move said lever from its fully advanced record playing position.

11. In a pre-set phonograph stop mechanism, the combination with a phonograph starting lever, said lever adapted to have normal and advanced operative positions, a phonograph turn-table, motor means to rotate the said turn-table, said motor means being responsive to the movement of the tone arm to substantially its end-of-record playing position to 115 operate the said switch, a spring tending to maintain said lever in normal position, said spring when said lever is moved to said ad-

vanced position being adapted to exert a pressure to maintain the said lever in said advanced position.

10. In a pre-set phonograph stop mechanism, the combination with a phonograph starting lever, said lever adapted to have normal and advanced operative positions, a phonograph turn-table, motor means to rotate the said turn-table, said motor means being responsive to the movement of the said lever from its normal to its advanced position to rotate the said turn-table, electro-magnetic means adapted when energized to restore the said lever from its advanced to its normal position, an electric switch controlling the energization of the said electro-magnetic means, and means responsive to the movement of the tone arm to substantially its end-of-record playing position to 20 operate the said switch, and electrical motor elements for the said motor, said switch contacts being included in the energization circuit of the said electrical motor elements.

11. In a pre-set phonograph stop mechanism, the combination with a phonograph starting lever, said lever adapted to have normal and advanced operative positions, a phonograph turn-table, motor means to rotate the said turn-table, said motor means being responsive to the movement of the said lever from its normal to its advanced position to rotate the said turn-table, electro-magnetic means adapted when energized to restore the said lever from its advanced to its normal position, an electric switch controlling the energization of the said electro-magnetic means, and means responsive to the movement of the tone arm to substantially its end-of-record playing position to 30 operate the said switch, and electrical motor elements for the said motor, said switch contacts being included in the energization circuit of the said electrical motor elements.

to operate the said switch, a spring associated with the said starting lever and adapted to accelerate its movement toward normal position, said spring being so disposed relative to the said lever that it will be ineffective to tend to move said lever from its fully advanced record playing position, and electrical motor elements for the said motor, said switch contacts being included in the energizing circuit of the said electrical motor elements. 40

12. In a pre-set phonograph stop mechanism, the combination with a phonograph starting lever, said lever adapted to have normal and advanced operative positions, a phonograph turn-table, motor means to rotate the said turn-table, said motor means being responsive to the movement of the said lever from its normal to its advanced position to rotate the said turn-table, electro-magnetic means adapted when energized to restore the said lever from its advanced to its normal position, an electric switch controlling the energization of the said electro-magnetic means, and means responsive to the movement of the tone arm to substantially its end-of-record playing position to 50 operate the said switch, and electrical motor elements for the said motor, said switch contacts being included in the energization circuit of the said electrical motor elements.

13. In a pre-set phonograph stop mechanism, the combination with a phonograph starting lever, said lever adapted to have normal and advanced operative positions, a phonograph turn-table, motor means to rotate the said turn-table, said motor means being responsive to the movement of the said lever from its normal to its advanced position to rotate the said turn-table, electro-magnetic means adapted when energized to restore the said lever from its advanced to its normal position, an electric switch controlling the energization of the said electro-magnetic means, and means responsive to the movement of the tone arm to substantially its end-of-record playing position to 60 operate the said switch, and electrical motor elements for the said motor, said switch contacts being included in the energization circuit of the said electrical motor elements.

In witness whereof, I have hereunto signed my name this 10th day of April, 1922.

WM. W. DEAN.
